UNITED STATES PATENT OFFICE.

GEORGE B. VARNUM AND LOUIS G. SEXTON, OF LOS ANGELES, CALIFORNIA.

LOCK.

Application filed January 15, 1923. Serial No. 351,634.

To all whom it may concern:

Be it known that we, GEORGE B. VARNUM and LOUIS G. SEXTON, citizens of the United States, residing at Los Angeles, in the county of Los Angeles, State of California, have invented new and useful Improvements in Locks, of which the following is a specification.

This invention relates to a lock and more particularly to a door lock adapted for use in connection with a safe deposit compartment door, or the like, which requires two keys for its operation. It is an object of the invention to provide an improved lock of this character which is simple and effective.

A particular object of the invention is to provide a lock of the character above set forth which can only be opened by the use of a main key and a guard key and from which the guard key can not be removed until the main key is removed; it being possible however, to lock the door with the main key only.

When the lock provided by the present invention is used in connection with a safe deposit compartment door it makes it necessary for the renter (holding the main key) and the guard (holding the guard key) to both place their key in the lock before it can be operated, and prevents a renter from leaving his key in the lock after the door is open, as it makes it necessary for the renter's key to be removed before the guard key can be removed. This manner of operation prevent renters from leaving their keys in the lock to be lost or removed by unauthorized persons. The fact that the lock can not be operated to close and lock the door without the renter's (main) key prevents renters from putting their bond boxes into the wrong compartments and subsequently closing or locking the doors thereof.

Further objects and features of the invention will be best understood from the following detailed description of a preferred embodiment of the invention throughout which reference is had to the accompanying drawings, in which—

Fig. 1 is a transverse sectional view of the forward portion of a safe deposit compartment showing the lock provided by the present invention in connection with the door thereof; Fig. 2 is an enlarged section of the lock taken as indicated by line 2—2 on Fig.

1, showing the lock in its locked or thrown position; Fig. 3 is a sectional view taken as indicated by line 3—3 on Fig. 2, showing the guard key in its actuated position; Fig. 60 4 is a view similar to Fig. 2 showing the lock in its actuated or released position; Fig. 5 is a view taken as indicated by line 5—5 on Fig. 4; Fig. 6 is a view taken as indicated by line 6—6 on Fig. 3; and Fig. 7 65 is a view similar to Figs. 2 and 4 showing both bolts in their out positions as they are when the door is open and the keys are removed from the lock.

Throughout the drawings numeral 10 designates a door hinged at 11 to one side of a suitable casing 12. Although the present invention is herein referred to in particular as adapted for use in connection with doors of safety deposit compartments and although it is shown in the drawings in connection with a door of that character, it will be understood that the invention is not in any way limited or restricted to such use or application but that it may be used in connection with doors and devices of various kinds. The mechanism embodying the invention may be arranged or carried in a suitable casing 13 which may be mounted in any suitable manner on or in the door 10. 80 The bolt 14 of the lock which extends from the casing 13 is adapted to co-operate with a suitable bolt plate or keeper 15, as clearly shown in the drawings. In the particular form of the invention shown in the drawings the keeper 15 is a plate provided with an aperture 16 adapted to receive the bolt 14 but not of sufficient size to receive the guard bolt 17.

The mechanism carried in the casing 13 95 comprises, a plurality of tumblers 18 adapted to be operated by the main key 19, and a single tumbler 20 adapted to be operated by the guard key 21. A pivot pin 22 extends through a suitable slot 23 in the tail piece 100 24 of bolt 14 and carries, above the tail piece 24, the tumblers 18 and the tumbler 20; the tumbler 20, however, being adjacent to the tail piece 24, as clearly shown in the drawings. The tumblers are provided with 105 suitable springs 26 by which they are normally kept in the position shown in Fig. 2.

The main key 19 is adapted to be inserted into slot 27 in the rotatable key post 28 so that it will engage the tumblers 18 when 110 rotated and thereby cause the notches or slots 29 in the tumblers to come in line or

register with each other in the position shown in Fig. 4. When the tumblers 18 have been actuated by the main key 19 so as to be in the position shown in Fig. 4, and 5 the tumbler 20 is actuated by the guard key 21, as will be hereinafter described, so that its slot 30 is also in line with the slots 29, the stump 31 which extends from the tail piece 24, is located to freely enter the 10 notches 29 and 30 when they are in line, as just described. When the main key 19 is turned sufficiently the arm 33, which extends from the key post 28, engages the shoulder 35 formed in the tail piece causing movement 15 of the tail piece. The various parts are so arranged and proportioned that the main key 19 actuates the tumblers 18 to cause the slots 29 to come in alignment just before the arm 33 engages the shoulder 35, 20 thereby positively assuring alignment of the slots 29 before the tail piece 24 is moved. The construction herein so far described is more or less common to devices of this character and it will be understood how 25 movement of the tail piece 24 by engagement of the arm 33 with the shoulder 35 will cause withdrawal of the bolt 14 from the aperture 16 in keeper 15, and will thereby allow the door 10 to be opened. The particular arrangement and number of tumblers, etc., herein set forth is merely typical and it will be understood that the invention is not in any way limited or restricted to such arrangement or number of tumblers, 30 etc., but may be embodied in a variety of locks arranged to be operated by two keys.

The tumbler 20 which is adjacent to the tail piece 24 is not actuated by the main key 19 but can only be moved by the guard 40 key 21. The guard key 21 is adapted to be inserted in the slot 38 in rotatable key post 39 and when in place in the key post it may be rotated with the key post so as to engage and move arm 40 which extends from the 45 tumbler 20. In Fig. 3 it is clearly shown how the guard 21 engages the arm 40 of tumbler 20 and it will be readily understood how a sufficient amount of movement of the tumbler in the direction indicated by the 50 arrow in Fig. 2 will cause the slot 30 in it to be brought in line with the stump 31. The spring 26 in connection with the tumbler 20 normally keeps it in the position shown in Fig. 2 and thereby makes it impossible to 55 bring the slots 29 and 30 into line with each other and the stump 31 with the use of a single key. It will be readily understood how actuation of the tumbler 20 so as to bring the slot 30 into line with the stump 31 allows the main key 19 to cause movement 60 of the tail piece 24 of bolt 14 after being rotated sufficiently to bring the slots 29 into alignment with the stump 31, as hereinbefore described. Movement of the 65 tail piece 24 in the direction indicated by

the arrow in Fig. 2 causes withdrawal or retraction of the bolt 14 from the aperture 16 in keeper 15 thereby allowing the door 10 to be opened.

When the main key 19 is inserted in the 70 groove 27 in key post 28 tumbler 42 carried in the outer portion of the key post 28 is depressed or moved outwardly by the back edge 43 of the key. The tumbler 42 engages a lever 44 pivotally connected at 45 to the key post 28, and is normally moved so as to extend into the slot 27 by a suitable spring 46 arranged in connection with the lever 44 as clearly shown in Fig. 3. Arm 47 of lever 44 engages arm 48 of bell crank 80 49 which is pivotally mounted at 50 in the casing and actuation, or depression, of the plunger 42 by the key 19 allows the spring 51, in connection with the bell crank 49, to move the bell crank in the direction indicated by the arrow in Fig. 4. Such movement of the bell crank 49 causes the arm 52 thereof to move to a position where it will engage notch 53 in the guard key 21, when the guard key is in place in the key post 39 90 and is in position relative to the casing 13 so that it can be withdrawn from the lock. The portion 55 of the casing 13 which holds the key post 39 in place in the lock is provided with a suitable notch 56 which makes 95 it necessary to have the key post 39 in a certain position (in the position shown in Fig. 2) before the key can be inserted in or withdrawn from the lock. A similar notch 57 is provided in the portion 58 of the casing which holds the key post 28 in place in the casing so as to make it necessary to have the key post 28 in a certain position (the position shown in Figs. 2 and 3 in the drawings) before the main key 19 can be 100 inserted or withdrawn from the lock. In the case of the key post 39 the notch 56 in the casing is so located that when the guard key 21 is inserted in the key post or when the guard key is in place in the key post and is in position to be withdrawn therefrom and the main key 19 is in place in key post 28 the notch 53 is in position to be engaged by the arm 52 of bell crank 49. The end of the guard key 21 has a beveled portion 59 115 which engages the arm 52 of bell crank 49 when the guard key 21 is being placed in the lock when the key 19 is in place, thereby causing the arm 52 to be pushed back a sufficient amount to allow insertion of the 120 key. When the key has been moved into its proper position in the key post 39 the arm 52 of the bell crank 49 is moved in the notch 53 by the spring 51. It will be readily understood how the mechanism and arrangement just described positively prevent removal of the guard key 21 from the lock while any portion of the main key 19 is in the key post 28. As soon as the main key 19 is completely removed from the lock or 130

- as soon as the main key 19 is moved so that its back edge 43 no longer engages the tumbler 42 the spring 46 causes the tumbler 42 to be moved into the slot 27 in the key post 5 28 and causes the bell crank 49 to be moved so that the arm 52 thereof no longer is in position to engage the notch 53 in the guard key 21, that is, the tumbler 42 and bell crank 49 are in the position shown in Fig. 2.
- 10 With the arm 52 of the bell crank 49 thus moved so that it no longer engages the notch 53 in the guard key 21 it is possible to remove the guard key from the lock by merely withdrawing it therefrom.
- 15 In order to be able to throw the bolt 14, by the main key 19 without the use of the guard key 21 when the door 10 is open, in order that the door may be closed and locked, a guard bolt 17 is provided in the 20 lock. The guard bolt 17 is arranged adjacent to one end of the bolt 14 and is arranged to co-operate with the keeper 15 so that it moves to its out position, as shown in Fig. 7, only when the door 10 is open. When 25 the door is in the closed position the keeper 15 engages the guard bolt 17, as shown in Fig. 2, and thereby prevents its complete outward movement. When the door is open, however, the guard bolt is free to move to its 30 outermost position (when the bolt 14 is in its outermost position). A projection 60 is provided on the tail piece 61 of the guard bolt 17 so that it will be engaged by the inner end 62 of the bolt 14 and thereby cause 35 the bolt 17 to be withdrawn or moved into the casing 13 with the main bolt 14. A suitable spring 64 is arranged in connection with the tail piece 61 of the guard bolt 17 so as to tend at all times to press or move the 40 guard bolt to its out or thrown position and sufficient play is provided between the inner end 62 of the bolt 14 and the projection 60 so that when the door 10 is open and the two bolts are in their out position the bolt 14 45 will be moved a short distance inwardly before the projection 60 is engaged by the end 62 of the bolt 14 to move the guard bolt 17. A suitable lug 65 is provided on the tail piece 61 of the guard bolt 17 so as to engage 50 lug 66 which extends from the arm 40 of tumbler 20 so as to move the arm 40 and therefore the tumbler 20 to its actuated position when the guard bolt 17 is in its out position or when the door 10 is open. The 55 spring 64 in connection with the tail piece 61 is stronger than spring 26 in connection with tumbler 20 thereby causing the tumbler to be moved to the position shown in Fig. 7, when the door is open so that the bolt 17 is 60 allowed to move to its outermost position. It will be particularly noted however, in Fig. 2, that when the bolt 17 is in engagement with the keeper 15 the lug 65 does not engage the lug 66 and therefore does not 65 actuate or move the tumbler 20 so that the slot 30 is in line with the stump 31 but makes it necessary to use the guard key 21 in order to actuate the tumbler 20. When the door is open, however, and the guard tumbler 17 is allowed to move to its outermost position as 70 shown in Fig. 6, the slot 30 in the tumbler 20 is in line with the stump 31 thereby allowing the bolt 14 to be actuated or withdrawn by the use of the main key only. Although the withdrawal of the bolt 14 causes withdrawal of the guard bolt 17 the play between the inner end 62 of the bolt 14 and the projection 60, allows the stump 31 to enter the slots 29 and 30 in the tumblers before the guard bolt 17 is actuated or moved sufficiently to allow the tumbler 20 to move so that the slot 30 is out of alignment with the stump 31. The result or action of the arrangement or mechanism is that when the door 10 is closed the bolt 14 can only be 75 withdrawn or moved by the use of the main key and the guard key 21, while when the door 10 is open the bolt 14 can be withdrawn or moved, in order to close the door, by the use of the main key 19 only. 80
- Having described a preferred form of our invention we do not wish to limit ourselves to the specific details hereinabove set forth but wish to reserve to ourselves any changes or modifications that may appear to those 85 skilled in the art or fall within the scope of the following claims. 90
- Having described a preferred form of our invention, we claim:
1. In a lock of the character described, a bolt adapted to be operated jointly by two keys, and means to prevent withdrawal of one of the keys from the lock while the other key is in the lock. 100
  2. In a lock of the character described, a bolt adapted to be retracted by simultaneous operation of two keys, and means to prevent withdrawal of one of the keys from the lock while the other key is in the lock. 105
  3. In a lock of the character described, a bolt adapted to be retracted by simultaneous operation of two keys, separate key posts for said keys, and means to prevent withdrawal of one of the keys from its key post until the other key is completely removed 110 from its key post. 115
  4. In a lock of the character described, a bolt adapted to be retracted by simultaneous operation of two keys, and means to prevent withdrawal of one of the keys from the lock until the other key is completely removed from the lock. 120
  5. In a lock, a bolt adapted to be retracted by simultaneous operation of two keys, means to prevent withdrawal of one of the keys from the lock except when said key is in a certain position, and means to prevent withdrawal of said key from the lock while the other key is in the lock, said means embodying a member actuated by the last men- 125 130

tioned key to engage the first mentioned key when it is in position to be withdrawn from the lock.

6. In a lock, a bolt adapted to be retracted by simultaneous operation of two keys, and means to prevent removal of one of the keys from the lock while the other key is in the lock, the last mentioned key being adapted to be withdrawn from the lock only when the bolt is in its thrown position.

7. In a lock, a bolt adapted to co-operate with a keeper, and be retracted by simultaneous operation of two keys when it is in engagement with the keeper, and be retracted by operation of one key when it is out of engagement with the keeper, and means in the lock to prevent withdrawal of one of the keys from the lock until the other key is withdrawn from the lock.

8. In a lock, a bolt adapted to co-operate with a keeper, and be retracted by simultaneous operation of two keys when it is in engagement with the keeper, and be retracted by operation of one key when it is out of engagement with the keeper, and means in the lock to prevent withdrawal of one of the keys from the lock until the other key is withdrawn from the lock, regardless of its operative condition.

9. In combination with a keeper, a door lock, the door lock comprising a bolt, a plurality of tumblers, the tumblers being adapted to be actuated by two keys to allow retraction of the bolt when the door is closed, each key actuating different tumblers, and means co-operating with the keeper to act in place of one of the keys when the door is open.

10. In combination with a keeper, a door lock, the door lock comprising a bolt, a plurality of tumblers, the tumblers being adapted to be actuated by two keys when the door is closed, each key actuating different tumblers, means co-operating with the keeper to act in place of one of the keys when the door is open, and means actuated by one of the keys to prevent removal of the other key from the lock while the key which actuates said means is in the lock.

11. In combination with a keeper, a door lock, the door lock comprising a bolt and a set of tumblers, the tumblers being adapted to be actuated by two keys when the door is closed, each key actuating different tumblers, means co-operating with the keeper to act in place of one of the keys when the door is open, thereby allowing retraction of the bolt by one key, and means actuated by the last mentioned key to prevent removal of the other key from the lock until the said last mentioned key is completely withdrawn from the lock and regardless of the operative condition of the lock.

12. In a lock of the character described, a bolt adapted to be operated jointly by two

keys, and a movable member to prevent withdrawal of one of the keys from the lock while the other key is in the lock.

13. In a lock of the character described, a bolt adapted to be operated jointly by two keys, and a pivotally mounted member to prevent withdrawal of one of the keys from the lock while the other key is in the lock.

14. In a lock of the character described, a bolt adapted to be operated jointly by two keys, a member adapted to be moved to prevent withdrawal of one of the keys from the lock, and a member moved by the other key when it is in the lock to actuate the first mentioned member.

15. In a lock of the character described, a bolt adapted to be operated jointly by two keys, an arm adapted to be actuated to prevent withdrawal of one of the keys from the lock, means for normally holding the arm out of the actuated position, and a member moved by the other key when it is in the lock to actuate the arm.

16. In a lock of the character described, a bolt adapted to be operated jointly by two keys, and a lever mechanism actuated by one of the keys to hold the other key in the lock while said first mentioned key is in the lock.

17. In a lock of the character described, a bolt adapted to be operated by joint operation of two keys at different parts of the lock, and means for preventing removal of one of the keys from the lock while the other key is in the lock.

18. In combination with a keeper, a door lock, the door lock comprising a bolt, a plurality of tumblers, the tumblers being adapted to be actuated by two keys to allow retraction of the bolt when the door is closed, each key actuating different tumblers, and a bolt cooperating with the keeper to act in place of one of the keys when the door is open.

19. In combination with a keeper, a door lock, the door lock comprising a bolt, a plurality of tumblers, the tumblers being adapted to be actuated by two keys to allow retraction of the bolt when the door is closed, each key actuating different tumblers, said means comprising a guard bolt adapted to act in place of one of the keys when completely extended and adapted to be prevented from becoming thus extended by the keeper when the door is closed.

20. In combination, a door, a keeper, a bolt adapted to engage the keeper, and means for operating the bolt requiring two keys for actuation when the door is closed and one key when the door is open.

21. In combination, a door, a keeper, a bolt adapted to engage the keeper, and means for retracting the bolt requiring the simultaneous operation of two keys for actuation when the door is closed and only one key when the door is open.

22. In combination, a door, a keeper, a bolt adapted to engage the keeper, and means for operating the bolt requiring two keys for actuation when the door is closed 5 and one key when the door is open, said means comprising tumblers adapted to be actuated by the keys to allow movement of the bolt, and a member adapted to act in place of one of the keys when the door is open.
23. In a lock a bolt adapted to be retracted by the joint action of two keys, a key post for one of the keys adapted to allow withdrawal of the key only when in a certain 15 position, and a movable member actuated when the other key is in the lock to prevent withdrawal of the first mentioned key from the lock.
24. In a lock of the character described, a bolt adapted to be operated by the joint action of two keys, and means adapted to prevent withdrawal of one of the keys from the lock when the other key is in the lock and allow placement of the first mentioned key 25 in the lock at any time.
25. In a lock of the character described a

bolt adapted to be operated by the joint action of two keys, a keeper adapted to be engaged by the bolt, and mechanism operated when one of the keys is in the lock to 30 prevent withdrawal of the other key from the lock.

26. In combination, a door, a keeper, a bolt adapted to operatively engage the keeper, a plurality of tumblers controlling 35 the operation of the bolt and adapted to be actuated to allow movement of the bolt by two keys, each key actuating different tumblers, means cooperating with the keeper when the door is closed to act in place of 40 one of the keys when the door is open, and a member actuated when one of the keys is in the lock to prevent withdrawal of the other key from the lock.

In witness that we claim the foregoing we 45 have hereunto subscribed our names this 3d day of January 1920.

GEORGE B. VARNUM.
LOUIS G. SEXTON.

Witness:

VIRGINIA BERRINGER.
